ENOCH S. YEUTZER, OF OTTAWA, ILLINOIS, ASSIGNOR OF ONE-HALF TO
CHARLES S. CULLEN AND RECTOR C. HITT, OF SAME PLACE.

HORSE HAY-FORK.

SPECIFICATION forming part of Letters Patent No. 327,639, dated October 6, 1885.

Application filed September 10, 1884. Serial No. 142,684. (No model.)

To all whom it may concern:

Be it known that I, ENOCH S. YEUTZER, a citizen of the United States, residing at Ottawa, in the county of La Salle and State of Illinois, have invented certain new and useful Improvements in Horse Hay-Forks, of which the following is a specification.

This invention relates to an improvement in horse hay-forks; and it consists in certain peculiarities of the construction and arrangement of the same, substantially as will be hereinafter more fully set forth and claimed.

In order to enable others skilled in the art to which my invention appertains, I will now proceed to describe its construction and arrangement, referring to the accompanying drawings, in which—

Figure 1 is a side elevation of my fork closed; Fig. 2, a similar view closed; Fig. 3, an edge view of the upper portion of the same; Fig. 4, a cross-section of the tines; and Fig. 5 is a modification of the latch.

A represents the tines of the fork, made of angle-iron and bent into the usual or any desired form. These tines are pivoted together at their upper ends, and their pivot-pin *a* projects upon one side for engagement with the latch.

B represents a slotted casting having a vertical slot, *b*, and upon each side a laterally-extending arm, *B'*, having its outer end provided with a small slot, *b'*, in which works a pin, *a'*, upon an arm, *a'*, of the tines. Through a small offset, *b'*, of the casting *B* runs the suspending-cord *c*, to the end of which is secured a plate, *C*, on which is pivoted a latch-hook, *C'*, having a shoulder, *c'*, and a locking and tripping lever, *C''*, to which is secured the tripping-line *c''*. The tripping-lever is also provided with a

spring, *d*, which keeps it always in position. Upon the back of the plate *C* is a transverse tooth or beveled lug, *d'*, adapted to engage with a series of transverse serrations, *d''*, upon the casting *B*, as in Fig. 3.

In operation the fork is dropped upon the hay and the latch pulled down and engaged with the pin *a*. The rear end of the latch-lever being depressed the spring-holding lever drops behind the shoulder *c'* and secures it in position. The lifting-cord *c* being now raised draws up the inner ends of the tines and

throws their points together to firmly grasp the load, and it is held till the tripping-line is hauled upon, which at once releases the latch and allows the hay to drop. The plate *C* is secured to the casting *B* so as to rise and fall in its slot, either by a bolt, or, preferably, by the end of the cord *c* being passed through said cord and secured to a block upon its rear side. This is preferable, as it draws the plate *C* close to the casting and insures the projection *d'* and serrations *d''* engaging, thus locking the fork at any point. The manner of pivoting the inner ends of the tines and permitting them to turn upon an adjustable fulcrum in the arms *B'* causes them to open much farther than usual and grasp a greater amount of hay. The tines being made of angle-iron are very light and strong, and reduces both the weight and cost of manufacture.

In Fig. 5 is shown a slight modification of the latch, in which only one pivoted bar is used with the tripping-line attached.

Having thus fully described my invention, what I claim as new, and desire to secure by Letters Patent, is—

1. In a hay-fork, the combination, with a vertically-slotted casting having lateral arms, of the fork-tines having their inner ends pivoted together and adapted to rise and fall in the slot and fulcrumed adjustably in the lateral arms, substantially as shown and described.

2. In a hay-fork, a slotted casting having slotted lateral arms, in combination with a pair of fork-tines fulcrumed in the arms and pivoted together at their inner ends, and a lifting-latch sliding vertically in the slotted casting, substantially as shown and described.

3. In a hay-fork, the casting *B*, formed with serrations *d'*, in combination with the latch-plate *C*, having a beveled lug, *d'*, upon its rear side, substantially as and for the purpose set forth.

4. The plate or casting *B*, having slot *b* and serrations *d''*, in combination with the latch-plate *C*, cast with a beveled projection, *d'*, and the suspending-cord *c*, passed through both the latch-plate and the slotted casting and secured to a block upon its other side, substantially as and for the purpose set forth.

5. The casting *B*, having slot *b* and slotted

arms B', in combination with the tines A, connected at their inner ends by a pivot, *a*, working in the slot *b* and fulcrumed at *a'* in the slotted arms, substantially as and for the purpose set forth.

6. The slotted casting B, having slotted arms B', and the tines A, fulcrumed in the slotted arms and having a projecting pivot-pin, *a*, connecting their inner ends, in combination with the plate C, latch C', having shoulder *c'*, and tripping-lever C², substantially as and for the purpose set forth.

7. A hay-fork having its tines made of angle-iron, substantially as and for the purpose set forth.

In testimony whereof I affix my signature in presence of two witnesses.

ENOCH S. YEUTZER.
